UNITED STATES PATENT OFFICE.

CHARLES P. KUEHNER, OF PROVIDENCE, RHODE ISLAND.

UMBRELLA-FRAME.

1,326,672.

Specification of Letters Patent. Patented Dec. 30, 1919.

Application filed March 14, 1918. Serial No. 222,289.

To all whom it may concern:

Be it known that I, CHARLES P. KUEHNER, a citizen of the United States, and resident of the city of Providence, in the county of

5 Providence and State of Rhode Island, have invented certain new and useful Improvements in Umbrella-Frames, of which the following is a specification.

This invention relates to joints for umbrella frames, and has for its object to provide a joint member which is formed separate and independent of the frame proper, the different members of the joint being secured in their respective frames by the folding of the walls of the frame thereover.

In practice it is customary to form the frame members of an umbrella of steel and to make them U-shape in cross section.

Various constructions have been employed for connecting the end of the spreader member to the rib member by bending or folding the metal of which the frame is constructed, but owing to the fact that the umbrella is so often subjected to moisture, the steel quickly becomes corroded, and the joints broken. Therefore to obviate this difficulty and to provide an umbrella whose joint will last indefinitely, I have formed the joint members separate and independent of the frame members, and of a heavier stock than that of the frame; and by forming them separately I am also enabled to make them of a non-corrosive metal such as brass, aluminum or the like.

35 With these and other objects in view, the invention consists of certain novel features of construction, as will be more fully described, and particularly pointed out in the appended claims.

40 In the accompanying drawing:

Figure 1— is a view of a portion of the frame members of an umbrella in spread position and partly in section illustrating the operation of my improved joint members.

Fig. 2— is a detail of the pintle member of the joint.

Fig. 3— is a detail of the eye-member of the joint showing the same as cut from sheet stock before being folded over the bridge-pintle and upon itself.

Fig. 4— is a perspective view showing the pintle-member, and the eye-member as connected to the pintle-member by being folded thereover.

Fig. 5— is a view showing a portion of

the under side of the frame-member in which the pintle-member is secured by the folding of the walls of the frame thereover.

Fig. 6— is a sectional end view showing the body parts of the eye-member in the trough of the frame-member and said parts being secured together therein by the bending of the walls of the frame thereover.

Referring to the drawings, 10 designates the staff of an umbrella on the outer end of which is mounted the eye-member 11 to which the ends 12 of the ribs 13 are hinged.

The inner end 14 of the spreader members 15 is hinged at 16 to the sleeve 17 which is mounted to slide on the staff and be secured in raised position by means of the spring wire catch 18.

It is found in practice desirable to provide a strong and durable joint where the outer end of the spreader member is connected to the rib-member. To accomplish this in a simple and practical way, I have provided a pintle-member 19 which is preferably formed independent of the rib and of brass, or other suitable non-corrosive material, the same being constructed with a body portion 20, and a neck portion 21 which is turned outwardly to extend from the plane of the body portion.

The end of this neck is provided with a cross-bar 22 which forms a joint-pintle to which the other member of the hinge is connected.

The body of this pintle member is provided with laterally extending portions 23 which serve to positively prevent endwise movement of the pintle-member in its frame-member when the walls of the latter are folded over this body portion of the member in the manner illustrated in Fig. 5. The other member of this hinge-joint is made in the form of an eye-member preferably being struck out of sheet metal, as illustrated in Fig. 3, having a central opening 24 through which the neck 21 of the pintle-member extends, whereby the body parts 25 of this eye-member may be folded over upon itself, as illustrated in Fig. 4, causing the bridging portion 26 thereof to form loops over the cross-bar 22 of the pintle-member thus providing a hinge which is most strong and durable.

In order to secure the folded parts of this eye-member together, they are passed into the trough-shaped end of the spreader mem-

ber 15, and the walls 25 of this spreader member are folded thereover, as illustrated in Fig. 6, which construction serves a double purpose; first, the rolled-in walls secure this 5 eye member in the spreader member; and second, the rolled-in walls firmly secure the folded parts of the eye member together over its pintle against any possibility of separation. The side edges of the eye member are provided with laterally extending portions 27 so that when the walls of the frame are folded thereover, the eye member is securely locked therein against any possibility of relative endwise motion.

15 It is found in practice that in some cases the hinge members may be reversed, that is the eye member may be held in the rib and the pintle member held in the spreader in which case the eye member would be offset 20 instead of the pintle member.

The foregoing description is directed solely toward the construction illustrated, but I reserve the privilege of resorting to all the mechanical changes to which the device is susceptible, the invention being defined and limited only by the terms of the appended claims.

I claim:

1. The combination with an umbrella frame, the members of which are constructed 30 in U-shape in cross section, of a pair of hinge joint members comprising a pintle member having a body secured between the walls of one of said frame members, and an eye member formed of flat stock folded upon 35 itself over the cross bar of the T-head of said pintle member, the folded portions of said eye member being secured together and

the eye-member itself being held in the opposite frame member by folding the side walls 40 of the latter over the doubled portions of the former.

2. The combination with an umbrella frame, the members of which are constructed U-shape in cross section, of a pair of hinge joint members comprising a pintle member having a body secured between the walls of one of said frame members, said pintle member having a T-shaped head offset from the plane of the body portion and extending outwardly laterally from said frame member, and an eye member formed of flat stock folded upon itself over the cross bar of said T-head, the folded portions of said eye member being secured together between the 50 walls of the opposite frame member.

3. The combination with an umbrella frame the members of which are constructed U-shape in cross section, of a pair of hinge joint members comprising a pintle member having a body secured between the walls of one of said frame members, and an eye member formed of flat stock folded upon itself over the cross bar of the T-head of said pintle member, the folded portions of 60 said eye member being secured together between the walls of the opposite frame member, one of said hinge joint members being offset to project laterally from the plane of the frame member in which it is held.

In testimony whereof I affix my signature in presence of one witness.

CHARLES P. KUEHNER.

Witness:

HOWARD E. BARLOW.
